UNITED STATES PATENT OFFICE.

CALEB E. SUMMERS, OF KANSAS CITY, MISSOURI, ASSIGNOR TO LAURA A. SUMMERS, OF OAKTOWN, INDIANA.

CARBURETER.

1,188,572.

Specification of Letters Patent. Patented June 27, 1916.

Application filed September 8, 1913. Serial No. 788,626.

To all whom it may concern:

Be it known that I, CALEB E. SUMMERS, a citizen of the United States, residing at Kansas City, in the county of Jackson and State of Missouri, have invented certain new and useful Improvements in Carbureters; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to carbureters and has for its principal object, to provide a carbureter whereby fuel may be delivered to the cylinder of a motor in measured quantities, and whereby the delivery is automatically regulated to meet the changing requirements for varying load and speed of the motor, and varying temperature and barometric pressure. In accomplishing this object I have provided a carbureter, comprising a measuring device which is operable from the crank shaft of the motor with which the carbureter is used, and is under the control of a temperature and pressure regulator, so that speed of the fuel delivering mechanism is controlled by speed of the motor, and also by the temperature or pressure of the fluid medium within the carbureter.

In particular the invention comprises certain improved details of structure the preferred forms of which are illustrated in the accompanying drawings, wherein:

Figure I is a view of a portion of an automobile having a motor equipped with a carbureter constructed according to my invention. Fig. II is an enlarged perspective view of the carbureter illustrating its mounting on the motor. Fig. III is a vertical section on the line III-III, Fig. II, illustrating the mechanism whereby the fuel feeding parts are actuated from the crank shaft of the motor. Fig. IV is a cross-section on the line IV-IV, Fig. II, showing the fuel feeding mechanism and a part of the regulator. Fig. V is a vertical section on the line V-V, Fig. IV. Fig. VI is a detailed perspective of a portion of the fuel feeding chamber showing the intake for fuel from the chamber into the feeding disk. Fig. VII is a detailed perspective of the liquid fuel cham-

ber. Fig. VIII is a detail perspective of the mechanism for driving the feed disk. Fig. IX is a vertical section on the line IX-IX, Fig. II, showing the regulator and throttle valve. Fig. X is a vertical section on the line X-X, Fig. IV, showing the connection between the regulator and the driving mechanism. Fig. XI is a detail elevation of the driving ratchet and regulator trip.

Referring more in detail to the parts:—1 designates a portion of an automobile, having a motor 2 of any suitable type, but here shown as comprising a plurality of cylinders having an intake manifold 3 and exhaust manifold 4; the vehicle and motor being illustrated merely to show the combination and use of the carbureter without the idea of limiting such combination and use to a vehicle or a motor of any particular type, as the improvements are adapted for use with motors of different types and particularly with aerial motors, because of this susceptibility to automatic regulation for variations in temperature and barometric pressure.

As better results may be obtained when the liquid, from which the fuel vapor is generated, is heated prior to its entrance into the motor, I provide a heater 5 of any suitable type, through which gases from the exhaust manifold are delivered, to heat the liquid prior to its delivery to the mixer, and interpose this element between the measuring device and a mixer, in order that measured quantities of liquid may be passed through the heater after the fuel has been measured and prior to its ultimate vaporization.

The measuring device comprises a casing 6, which is suitably mounted adjacent the motor and heater, and incloses a chamber 7 for the driving mechanism, and separate chamber 8 for the measuring mechanism, the separation being preferably accomplished by forming the measuring chamber in a head 9, which is attached to the casing 6 and covering the said chamber with a plate 10, which may be securely attached to the edges of said head so that its central portion over-lies and covers the chamber.

Journalized in the bearing 12 on the inner face of the plate 10 is a shaft 13, which extends inwardly through a stuffing box 14 in the head 9 and extends through the driv-

ing chamber 7; the inner end of the shaft being journaled in a socket 15 in a boss 16 on the outer end of the regulator shaft 17. Fixed on the shaft 13, by means of a key 19, which is carried on said shaft and located in a seat 20 in its inner face, is a disk 21, which is held against the inner face of the plate 10 by a spring 22 that is mounted on said shaft and bears against the stuffing box 14, and has wiping contact with the inner face of the disk. The outer face of the disk is provided with pockets 24 which are adapted for travel past recesses 25' in the inner face of a centering disk 25 on the plate 10, so that liquid fuel contained within said chamber may fill the pockets, and for travel along and in close contact with bosses 27 on the face of the disk, so that when the pockets are filled and the disk is revolved the liquid fuel may be trapped in said pockets and carried to an outlet port 26 in the plate 10.

The plate 10 is provided with a boss 28, having a conduit 29 communicating with the outlet port from the measuring chamber, and with a conduit 30 having an outer end 31 opening to the atmosphere, and an inner end 32 lying adjacent the outlet port of the measuring chamber, so that suction through the tube 33 that connects the conduit 29 with the heater, and through various other conduits and chambers with the intake manifold will draw liquid from the pockets 24 as the latter register with the outlet port, together with the air which enters through the open conduit 30 and communicates with the disk pockets, in order to enable the pockets to empty by suction in the discharge conduit.

As air from the open conduit 30 will be carried over into the feeding chamber, and, when accumulated therein, exert pressure on the liquid which might interfere with the proper feeding from the supply, I provide the liquid chamber with a vent 35 having a tube 33 leading to a point above the level of liquid in the supply tank 37, so that air in the feeding chamber may be exhausted to obviate accumulation and the resultant pressure.

The supply tank 37 may be located at any convenient point and connected with the feeding chamber by a conduit 38 which is mounted on an intake nipple 39 on the bottom of the head 9, and has a channel 40 opening into the lower portion of the feeding chamber.

The actuating mechanism for revolving the feeding disk comprises a ratchet wheel 42, which is fixed on the shaft 13 within the chamber 7, and is adapted for actuation by pawls 43 (Figs. III and XI), which are pivotally mounted on the ends of the arms 44 that are in turn pivotally mounted on

the shaft 13 and provided with collars 45, whereby they are held against the ratchet wheel.

The pawls 43 are arranged oppositely, and are adapted for alternate engagement with the teeth of the ratchet wheel 42, the pawls being yieldingly tensioned against the ratchet wheel by the springs 49 mounted on a lug extended from the pawls. As the pawls are carried backward and forward simultaneously on the pivotally mounted oscillating arms 44, the teeth of the pawls engage alternately with the teeth of the ratchet wheel, so that the ratchet wheel is given a forward impulse at each oscillation, one pawl carrying the ratchet forward, while the other simultaneously slides backward over the teeth.

The means for actuating the arms 44 comprises links 50, the forward ends of which are pivotally connected with the arms 44 and the rear ends thereof with opposite ends of a block 51, which is threaded on to the forward end of a plunger 52. The plunger 52 extends through an aperture 53 in the rear of the casing 6 into a socket 54 in the neck 55, whereby the case is mounted on the crank case of the motor, and through an aperture 56 in the crank case into contact with an eccentric 57 on the cam shaft 58 of the motor, the inner end of the plunger being provided with a head 59 for bringing the bearing surface against the cam. The outer end of the plunger is reduced to form a shoulder 60, and seated against said shoulder and against the base of the socket 54 is a coil spring 61, whereby the plunger is held in contact with the cam and against which it is forwarded by said cam to advance the arms 44 and carry the pawls over the ratchet wheel.

It is apparent that, with the mechanism described, the measuring disk will travel at a speed directly proportional to the speed of the motor, as it is actuated from the crank shaft of the motor.

After the liquid fuel has been delivered to the heater, as described, it passes through the heater and is delivered therefrom into a conduit 63, through which it is conducted to a combined mixer and throttle 64, preferably comprising a cone-shaped housing 65, having a port 66 communicating with the conduit 63 and an air port 67. Revolvably mounted within the housing is a cone-shaped valve 68, having ports 69 and 70 adapted for registration with the ports 66 and 67 respectively, and having a stem 71 extended through an aperture 72 in the base of the housing and connected, by any suitable means (not shown), with an ordinary throttle lever.

The housing 65 is mounted on a sleeve 74 that depends from a case 75 containing the

regulating mechanism. The interior of the case 75 has spaced annular rings 76 carrying a sleeve 77 to form an annular chamber 78 with which the interior of the sleeve 74 communicates, so that the mixture of fuel vapor and free air formed in the housing 65 travels up through the sleeve 74 into the chamber 78, from which it is delivered into a conduit 79 that communicates with the 10 intake manifold 3 of the motor.

Communication is established between the annular chamber 78 in the casing, and the regulator chamber, through a spiral tube 81, one end of which opens into the regulator 15 chamber and the other end into a port 82 in a casing 6 that opens into the annular chamber, so that the fuel vapor may pass from the annular chamber into the regulator chamber and exert a pressure on the 20 regulator contained therein equal to the pressure in the intake manifold of the motor. The connection between the manifold conduit and the regulator chamber being preferably spiraled as described, in order that 25 any sudden increase in pressure due to back-firing or other causes may be reduced before reaching the regulator chamber, and thereby obviating injury to the regulator.

The regulator which I prefer to use comprises a diaphragm 84, which is fixed at one 30 end to the base of the regulator chamber by a screw 85 and is free at the opposite end, that it may expand or contract longitudinally when the air contained therein is subjected to variations in temperature or barometric pressure. Inasmuch as the fuel requirements of the motor vary directly as to pressure and inversely as to temperature, it 35 is apparent that by connecting the diaphragm regulator with the fuel feeding mechanism, so that such mechanism may be interrupted when the diaphragm is expanded because of increase in temperature, or decrease in pressure of the air contained therein, regulation of the supply to the motor 40 may be secured for variations in temperature and barometric pressure as well as for speed and load.

As a preferred form of connection I pivotally mount an arm 87 within the casing 6 and connect same by link 88 with the free end of the diaphragm, so that when the diaphragm is expanded or contracted the link is moved outwardly or inwardly therewith. 50 The arm 87 is provided with a laterally directed pin 89, which is projected through a curved slot 90 in an arm 91, which is fixed on the shaft 17 having the boss 16 within which the shaft 13 that carries the driving ratchet and measuring disk, 42 and 21, is 55 revolvably mounted; the curve of the slot 90 being arranged to conform to the curve of the expansion of air within the diaphragm, under the influence of varying temperature 60 and barometric pressure, so that when the

diaphragm expands the shaft 17 is revolved in a determined ratio to the action of the diaphragm. Fixed on the end of the boss 16 is a trip-plate 93 which overlies the face of the ratchet 42 and is adapted for engagement 70 with lateral extensions 94 on the pawls 43, so that when the trip-plate is actuated by expansion of the diaphragm, the pawls are lifted from their contact with the ratchet and the driving engagement thereof with 75 the ratchet interrupted to a degree corresponding with the degree of expansion of the diaphragm, with the result that travel of the measuring disk is reduced and a less supply of fuel delivered to the motor. 80

The diaphragm is preferably arranged to take care of the motor for the lowest possible temperature and pressure without actuation of the shaft 17, so that all of the regulation is had for higher temperatures or lower 85 pressures, the curve of the slot 90 being that for increasing temperature or decreasing pressure.

In using the carburetor, presuming the parts to be constructed and assembled as directed, when the motor is in operation each revolution of its crank shaft moves the plunger of the feeding mechanism inwardly for one stroke against the tension of the spring 61. When the plunger is moved inwardly 90 the pawl arms are moved forwardly, so that the upper pawl slides idly over the ratchet teeth, and the lower pawl pushes against and actuates the ratchet. Backward travel of 95 the plunger, under tension of the spring, reverses the action of the pawls, so that the ratchet is operated during both the forward and backward travel of the plunger; the ratchet wheel, being rigidly attached to its shaft, causes the shaft to revolve and carry 100 the measuring disk around therewith, so that the pockets in the outer face of the disk are carried through the recess in the end plate of the disk chamber to fill with fluid fuel, and, after passing the recess, move around 105 to bring the fuel plates into registration with the port leading to the conduit of the tube that connects with the heater. As the supply tank is arranged to constantly maintain 110 the feeding chamber supplied with liquid fuel, a charge of such liquid is always conducted to the outlet port of the chamber, whenever a fuel pocket is brought into registration with the port. As the feeding mechanism is operated directly from the 115 crank shaft of the motor, the motor is in operation whenever the charges of fuel are brought into feeding position, so that suction exists in the feeding conduits that tends to draw the charges of liquid out of the pockets and into the feeding conduit, the free-air inlet to the pockets permitting the suction in the pockets, so that the latter may be emptied. After the charges of liquid 120 have been drawn from the measuring pock- 125

ets, they are conducted through the combined mixer and throttle, where the fluid mixture of the fuel liquid, and whatever air has been carried over from the opening 5 above the feeding port from the measuring disk, is mixed with free air admitted to the mixer and carried up through the annular chamber about the regulator, and into the manifold, and finally into the cylinders, to 10 be exploded.

The annular chamber through which the fuel vapor passes to reach the intake manifold of the motor is connected with the regulator chamber in such a manner that the contents of the regulator chamber are maintained at the same temperature and pressure 15 as the fuel vapor that is delivered to the cylinders, although the connection is such that sudden increase in temperature or pressure 20 will be reduced before reaching the regulator chamber, thereby obviating injury to the relatively delicate diaphragm.

With the regulator constructed and connected with the feeding mechanism as described, the parts will normally operate 25 without automatic regulation, except by the speed or load of the motor, as the diaphragm and the parts connecting same with the pawl trip-plate are adapted for use under normal 30 temperatures and pressures. If, however, the temperature of the contents of the regulating chamber are raised above normal by heating of the carbureter by surrounding atmosphere or other causes, the air within the 35 diaphragm will expand and push the arm 87 outwardly to rock the arm 91 and shaft 17, so that the trip-plate on the end of the shaft will engage the pawls that actuate the ratchet and cause said pawls to miss connection 40 with the ratchet during part of their travel, and thereby reduce travel of the ratchet and consequently of the feeding disk, so that a less charge of fuel liquid is delivered to the mixing chamber; the curve 45 of the slot in the arm 91 determining the amount of reduction of the feed of liquid for each degree of expansion of the diaphragm, so that the proper quantity of fuel is delivered 50 into the engine cylinders for the requirements of the motor at the existing temperature. When the temperature is again low the diaphragm will contract and the original feed of liquid be resumed. Likewise 55 when a lower barometric pressure is encountered on account of changing conditions at the same level, or by the motor being sent into a higher elevation, the air within the diaphragm is allowed to expand, so that results corresponding to those effected by increase 60 in temperature are secured. It is apparent that this susceptibility to automatic regulation by temperature and barometric condition renders the carbureter particularly valuable for use in connection with aerial 65 motors, as the constant regulation usually

necessary during the flight of an aerial craft is performed automatically with my improvements, so that the only manual regulation which is required is that of the throttle.

Having thus described my invention, what I claim as new therein and desire to secure by Letters-Patent, is:—

1. A carbureter comprising a fuel chamber, having a pair of bosses on its inner face 75 and having a port in one of said bosses, a disk having pockets in its face adapted for travel past the inner face of the case in contact with said bosses and past said port, means for revolving said disk, and a mixer 80 connected with said port and adapted for receiving fluid from the disk pockets, substantially as set forth.

2. A carbureter comprising a fluid chamber, having a vertical head-recess and a port spaced from said recess, a shaft revolvably mounted in said chamber, a disk mounted on said shaft and having pockets in its face adapted for travel past the recess and port, a spring for normally tensioning said disk 90 against the head of the chamber, and a mixer connected with said port, for the purpose set forth.

3. A carbureter comprising a fluid chamber, having a recessed part and a port, a disk revolvably mounted in the chamber and adapted for travel past the recessed part and port, and a boss adjacent said port having separate delivery and air-intake conduits in communication therewith, for the purpose 100 set forth.

4. A carbureter comprising a revoluble shaft, a fluid mechanism adapted for actuation by the shaft, a ratchet member mounted on said shaft, pawl arms pivotally mounted on said shaft, pawls pivotally mounted on said arms and adapted for operative engagement with the ratchet member; a plunger, a head mounted on said plunger, links pivotally connecting the pawl arms with said head and means governable by atmospheric conditions for lifting said pawls.

5. A carbureter comprising a revoluble shaft, a fluid fuel mechanism adapted for actuation by the shaft, a ratchet member mounted on said shaft, pawl arms pivotally mounted on said shaft, oppositely directed pawls pivotally mounted on said arms and adapted for operative engagement with the ratchet member, a plunger, a head mounted on said plunger, links pivotally connecting the arms with said head and air temperature and pressure controlled means for lifting said pawls.

6. A carbureter comprising a revoluble 125 shaft, a fluid measuring mechanism adapted for actuation by the shaft, a ratchet member mounted on said shaft, pawl arms pivotally mounted on said shaft, oppositely directed pawls on said arms, springs for yieldingly 130

5 tensioning said pawls to contact with the ratchet member; a plunger, a head mounted on said plunger, links pivotally connecting the arms with said head and a regulator for determining the effective engagement of said pawls with said ratchet member.

7. A carbureter comprising a revoluble shaft, a measuring disk fixed on said shaft, a ratchet member fixed on said shaft, oppositely directed pawl arms pivotally mounted on said shaft and adapted for independent actuation, oppositely directed pawls pivotally mounted on said arms, springs for yieldingly tensioning said pawls to actuate with the ratchet member, a plunger having a head member pivotally connected with said arms, means for actuating the plunger, whereby the ratchet member is driven at both the forward and backward reciprocation of the plunger, and a regulator for determining the effective engagement of said pawls and ratchet member.

8. A carbureter comprising a casing having a mixing chamber and a fuel measuring device, means for actuating said fuel measuring device, an expansion member operable upon variation of the temperature and pressure of its surrounding media, a sleeve separating the expansion member from the mixing chamber, means for indirectly connecting said mixing chamber with the interior of said sleeve, means for conducting fuel from the measuring device to said mixing chamber and means operable by said expansible member for controlling the means whereby said measuring device is actuated.

9. A carbureter comprising a casing having a mixing chamber and a fuel measuring device, means for actuating said fuel measuring device, a sleeve located in said mixing chamber, means for indirectly connecting the interior of said sleeve with said mixing chamber, an expansion member located within said sleeve and operable from the temperature and pressure of the media within the sleeve, means for conducting fuel from the measuring device to said mixing chamber, an automatic valve for supplying air to said mixing chamber, and means operable by said expansible member for controlling the means whereby said measuring device is actuated.

10. A carbureter comprising a fuel measuring device, means for actuating said device, a trip member for controlling said actuating means, a lever arm operatively connected with said trip member and provided with a slot, a pivoted arm having a pin slidably mounted in said slot, and an expansible regulator operatively connected with said pivoted arm and adapted for actuation by the variations in temperature and pressure of the local external media.

11. A carbureter comprising a fuel measuring device, means for actuating said device, a trip member for controlling said actuating

means, a lever arm operatively connected with said trip member and provided with a slot, a pivoted arm having a pin slidably mounted in said slot, and a temperature and pressure controlled regulator operatively connected with said pivoted arm.

12. The combination with a motor having a suitable intake, of a carbureter comprising a casing having separate chambers, a fluid measuring mechanism contained within one of said chambers, a regulator contained within another chamber and adapted for actuation by variations in temperature and pressure of the local external media; means for conducting fuel from the measuring device around the regulator chamber, a tortuous conduit connecting said fuel conduit with the interior of the regulator chamber, means for actuating said measuring device, and means connected with said regulator for controlling said actuating means.

13. The combination with a motor having a suitable intake, of a carbureter comprising a fluid fuel measuring device, a regulator chamber having a conduit therearound leading to the motor intake, and having a tortuous pipe communicating with said conduit, an extension on said conduit provided with separate fuel and air-intake ports, a valve located within said extension and having ports adapted for communication with the extension ports, means for actuating said valve, a fluid fuel measuring device, a conduit leading from the measuring device to the fuel intake port in said extension, and a regulator contained within the regulator chamber and operable from the temperature and pressure of the media in said chamber and adapted for controlling actuation of the measuring device.

14. A carbureter comprising a fuel measuring device, means for actuating said device, a trip member for controlling said actuating means, a lever arm operatively connected with said trip member, an expansible regulator adapted for actuation by the variations in temperature and pressure of the local external media, and a second lever connected with said regulator and having pin and slot connection with said first lever operating in direct proportion to the rate of expansion of the regulator.

15. A carbureter comprising separate regulator and measuring chambers, an expansible regulator in said regulator chamber adapted for actuation by variations in the temperature and pressure of the surrounding media, a fluid measuring device in said measuring chamber, means for actuating said device, a trip member for controlling said actuating means, a lever arm operatively connected with said trip member and having a slot conforming to the rate of expansion of said expansible regulator, and a second lever having a pin slid-

ably mounted in said slot and operatively connected with said regulator, for the purpose set forth.

16. A carbureter comprising a fluid fuel measuring chamber having an air vent in its upper part, a boss projecting into said chamber and having adjacent air inlet and fuel outlet ports, a disk having a plurality of pockets adapted for travel past said ports and in close contact with said boss to close said ports relative to said air vent, means for revolving said disk, and a temperature and pressure controlled regulator for governing the speed of said disk.
17. The combination with a motor having a suitable intake manifold, of a carbureter comprising a fluid fuel measuring chamber, a boss projecting into said chamber and having air intake and fuel outlet ports, a tube connecting the fuel outlet port with the intake manifold of the motor, a throttle in said intake manifold for varying the absolute pressure therein, a disk governed by the absolute pressure in the intake manifold and revolutely mounted in said measuring chamber and having a plurality of fuel pockets adapted for travel past said air inlet and fuel outlet ports, whereby the fuel in said

pockets is displaced by air from said air inlet port and exhausted through said fuel outlet port by virtue of the connection of the latter with the intake manifold of the motor.

18. The combination with a motor having a suitable intake manifold, of a carbureter comprising a fluid measuring chamber, a fluid measuring device in said chamber, means for actuating said measuring device, a regulator chamber, a regulator in said regulator chamber adapted for actuation from the temperature and pressure of the surrounding media for governing said measuring device, a conduit around said regulator chamber communicating with the intake manifold of the engine and with the air, a spiral tube connecting said regulator chamber with said conduit, a throttle valve at the air inlet end of said conduit, and a tube for conducting fuel in measured quantities from said measuring chamber to said conduit, for the purpose set forth.

In testimony whereof I affix my signature in presence of two witnesses.
